UNITED STATES PATENT OFFICE

1,942,105

APPARATUS FOR THE LIGHTING OF LU-
MINESCENT TUBES

Daniel Paul Albert André Kayser, Paris, France

Original application January 21, 1928, Serial No. 250,874, and in France February 11, 1927. Divided and this application July 29, 1929. Serial No. 381,961

7 Claims. (Cl. 176—124)

My invention is a division of my prior application Ser. No. 250,874, filed January 21st, 1928.

This prior application has for its object an apparatus and a method for the lighting of luminescent tubes chiefly neon tubes over a varying portion of their length. It provides means for controlling the portion of the tube which is illuminated and for producing special bead and nodule effects according, if desired, to a predetermined law of succession.

Now, whereas I have claimed broadly in my prior application a method and means for controlling the illumination of such tubes by means of modifications in the voltage of the tube feeding alternating or oscillating current, I propose, according to my present invention, to obtain a similar result through modifications in the intensity of the filament-heating current of a vacuum tube producing the oscillating current adapted to feed the luminescent tube and the voltage of which is consequently modified for the purpose specified.

Referring to the accompanying drawings—
25 Figure 1 is a view showing means for varying the intensity of the filament heating current of the electron discharge tube to vary the intensity of the current feeding the luminescent tube.

30 Fig. 2 illustrates another manner of obtaining the same result.

Figs. 3 and 4 show in two positions a modification comprising a motor driven frame.

Fig. 5 shows an electrically operated current 35 control device.

Fig. 6 shows an arrangement of a plurality of electronic tubes for feeding the glow tube.

In the embodiment shown in Fig. 1, my device comprises a three electrode tube for generating electric oscillations. The filament F of the said tube is inserted in a circuit comprising a battery 3 for heating said filament, an incandescent lamp 102 and a periodically actuated switch 2. The connections of the grid and of the plate are of any well known type adapted to produce self oscillation of the tube. For instance, as shown in Fig. 1, plate P is connected through battery 4 to an oscillating circuit comprising coil 5 and a condenser 6, said circuit being connected, on the other hand, to filament F. The grid is also connected to said filament through coil 7, which is inductively coupled with coil 5. The luminescent tube T which is to be controlled through my device is connected to the secondary of a transformer 8 the primary

of which is inserted in the plate circuit of tube 101. Incandescent lamp 102 may be either of the carbon filament type or of the metallic filament type. In the first case the resistance of lamp 102 gradually diminishes as the lamp heats up, whereas in the second case the resistance of the said lamp increases as it heats up. As the circuit of said lamp 102 is periodically opened and closed, it follows that the current is caused to flow periodically through filament F, the intensity of said current varying gradually due to the variations of resistance of the filament of lamp 102 consecutive to its being alternately heated up and allowed to cool. The heating of filament F is therefore periodically and gradually caused to vary and therefore the voltage impressed upon tube T is periodically caused to vary. I obtain thus in an absolutely automatic manner a progressive or regressive lighting of the tube T followed by extinction, this cycle repeating itself indefinitely.

Likewise with the same idea in view, I may use the expansion of a wire acting mechanically upon a resistance of variable character or other variable element which will vary the intensity of the current in the filament of the tube. Such an arrangement is shown in Figure 2.

As shown in said Figure 2, the filament of the electronic tube is fed by a current supply 103, generally a transformer. Another transformer 85 104 sends current through a wire 105 carrying through a preferably insulated rod 106, a lever 107 carrying at its extremity and electrically connected with a spirally wound resistance wire 108. Beneath the said wire is a cup 109 containing mercury and into which the wire 108 is adapted to dip to a greater or less extent, according to the position of lever 107. The said lever, the wire 108 and the mercury form part 90 of the filament exciting circuit 110 of tube 101. 95 When the wire 105 expands the lever 107 is lowered, the variable resistance of wire 108 is diminished, and as a result the filament of tube 101 becomes heated to a higher degree, which causes the progressive lighting and extinction of 100 the luminescent tube. Instead of a resistance, lever 107 may control a variable condenser or inductance, or the looseness of a coupling as disclosed in my prior specification No. 250,874.

It may be desirable to use a mechanical device 105 such as that represented in Figures 3 and 4.

As therein shown, the device comprises a reservoir 12 containing mercury and communicating by means of a small tube 13 with the bottom of a vertical chamber 14 in which is placed a 110

resistance wire 15 inserted in the filament exciting circuit of the vacuum tube 101.

The whole arrangement is adapted to turn about a shaft 16 under the action of an electric motor 17 fed by a source of current 18. One terminal of the said motor is adapted to be connected to the mercury contained in tube 13 by means of a conductor 19 whereas the other terminal thereof is connected through the source 18 and the conductor 20 with a contact 20' disposed within the chamber 14. A tube 21 joins the reservoir 12 with the top of the tube 14.

The operation of the device just described takes place as follows:

15 When the apparatus is in its normal position shown in Fig. 3 the mercury runs out of reservoir 12 through tube 13 and rises slowly in chamber 14.

As a result, the resistance afforded by wire 15 gradually diminishes which determines the progress in the lighting of the luminescent tube T. When the mercury has risen sufficiently in tube 14 to reach the contact 20', current is supplied to motor 17 which causes the whole arrangement 20 to turn about the shaft 16 thereof in such a manner as to bring the device into the position shown in Figure 4. The mercury then runs rapidly out of the chamber 14 through the large tube 21 into the reservoir 12, whereby the resistance afforded 25 by wire 15 increases suddenly and the illumination of the tube T decreases. The rotation thus produced may also act upon a switch controlling the feed current.

When all the mercury has returned into reservoir 12, the contact 20' is uncovered and the current is cut off from the circuit of motor 17. A suitable spring or weight 22 is adapted to subsequently return the apparatus to the position shown in Figure 3.

40 Another embodiment of the invention is illustrated in Figure 5.

In this figure an electrically controlled diagrammatically shown pendulum 23, of the type well known to those skilled in the art, carries a device serving to wind a spring 24 or to raise a weight serving the same purpose. The winding device may be of any well known type and is here represented as a pawl 26 adapted to engage a ratchet wheel 27 which is adapted to be retained by a fixed stop pawl 28. Suitable releasing means are provided for the pawl 28, and are shown here as an electro-magnet 29' under control of a contact 29 actuated by the wheel 27 during its movement of rotation, which magnet serves to 55 raise the stop pawl 28 at the moment desired.

This is accomplished as follows:

The said stop pawl remains raised during unwinding of the spring or fall of the weight by means of a suitable stop, which is released when 60 the unwinding operation is at an end.

The spring 24, when unwinding, causes the shaft 24' of the wheel 27 to turn, said movement of rotation being governed in any suitable manner, such as through an ordinary anchor escapement, 65 or blade wheel.

Associated with the shaft 24' is a device which is adapted to vary the intensity of the filament heating current during rotation of said shaft. The said device may be any suitable element 70 which is variable and capable of modifying the intensity of the current. As shown, it may comprise a rack 30 meshing with a pinion 31 fixed to a lever 32 of a rheostat 33 in the filament heating circuit.

75 It is to be particularly understood that this ar-

rangement is described by way of example and that the rack 30 could readily be replaced by any of the well known devices adapted to vary the intensity of a current or to act on a variable element capable of modifying same.

It will be obvious to those skilled in the art 80 that a suitable switch will make the lighting of the tube cease a certain time after the said tube has become totally illuminated and for a time 85 sufficiently long to allow the spring 24 to be rewound by the pendulum 23.

The device may be still further improved by 90 connecting a variable condenser either directly or through the medium of reducing gears, to the shaft of pendulum 23.

By suitably adjusting the apparatus, the pendulum continuing to oscillate during the unwinding of spring 24 (or fall of the weight), and during the entire duration of the complete lighting of the tube, the oscillation of the condenser 95 may be caused to determine precisely the effects of the movements of reciprocating displacement in one direction or the other of the luminous nodules in the said tubes. As a result, the phenomena which take place are as follows:

100 Progressive lighting of the luminescent tube.

Formation of nodules or beads in the completely illuminated tube which effect a to-and-fro movement.

Abrupt extinction, the cycle of phenomena 105 then beginning over again.

When the luminescent tubes are fed with alternating current transformed into pulsatory direct current by electronic tubes, only half of each alternating current wave can be used, e. g. the 110 current corresponding to the positive values of the alternating current.

As a result, obscure spots appear in the tube which produce very disagreeable luminous effects.

115 In order to overcome this disadvantage I have provided an arrangement which rectifies the current and permits both alternations of ordinary alternating current to be used for exciting the electronic tube. Such a device is represented 120 diagrammatically in Figure 6.

In said Fig. 6 alternating current, the voltage of which is say 110 volts, is taken from the mains and feeds two transformers connected in shunt relationship, one of these 36 being a high tension 125 transformer, and the other 37, a low tension transformer. The secondary winding of the low tension transformer feeds the filaments of two electronic tubes 41 and 42 through a conductor 38, a variable resistance 39 and a return conductor 40. This latter conductor may be provided with a periodically actuated switch. The grids of said tubes are connected to a central tap 43 of the secondary winding of the low tension transformer 37 through a tuning circuit comprising 130 a condenser 44 shunted by an inductance 45. A second condenser 46 shunted by a resistance 47 may also be disposed in the grid circuit, if desired.

The plates of the two electronic tubes 41 and 140 42 are connected to the terminals of the secondary winding of the high tension transformer 36. The mid-point 43' of the secondary winding of the high tension transformer 36 is connected to the mid-point of the secondary winding of the 145 low tension transformer 37 through a second tuning circuit including a variable condenser 48 and an inductance 49.

The two inductances 45 and 49 are disposed in inductive relation to each other, producing an 150

electro-magnetic inductive couple there-between.

It will thus be seen that by means of this device the tube 42 will be excited for one of the alternations of the alternating current supplied by the mains and the tube 41 will be excited for the other alternation thereof, in such manner that the arrangement of inductances 45, 49 will always be producing an oscillating field.

By coupling a winding 50 with the said inductances the said winding will be traversed by an oscillating current at a very high voltage capable of exciting the luminescent tube T. In the event that the tube employed is of such a nature that its excitation does not necessitate a very high voltage, the said tube may then be fed directly by the current passing through the inductance 49.

The intensity of the current flowing in the tube is controlled by adjusting one or both of the variable elements 44 and 48 in the arrangement shown with a view to obtain progressive or regressive lighting effects or movable and stationary nodules. In practice it is usually the condenser 44, which is used for this purpose as it gives the maximum sensibility.

It will be noticed that in principle the luminescent tubes may be kept illuminated by direct current or by low frequency alternating current of suitable voltage, once this illumination has been obtained by the high frequency current.

While I have disclosed what I believe to be the preferable forms of execution of my invention in the various examples set forth, I do not wish to be limited thereto, as various further changes may be made in the details of construction and the arrangement of parts without departing from the spirit of the invention comprehended within the scope of the appended claims.

What I claim is:

1. An apparatus for electrically controlling the degree of illumination of a luminescent tube and the formation of luminous beads or nodules therein comprising a three electrode electron tube adapted to act as a high frequency generator, a filament heating circuit for said tube, means for periodically opening and closing said filament heating circuit, means in said circuit for progressively changing the resistance thereof upon operation of the first mentioned means and means for feeding the luminescent tube with the high frequency variable voltage current generated by the electron tube.

2. An apparatus for electrically controlling the degree of illumination of a luminescent tube and the formation of luminous beads or nodules therein comprising a three electrode electron tube adapted to act as a high frequency generator, a filament heating circuit for said tube, means for periodically opening and closing said filament heating circuit, an incandescent lamp in said circuit for progressively changing the resistance thereof upon operation of the first mentioned means and means for feeding the luminescent tube with the high frequency variable voltage current generated by the electron tube.

3. An apparatus for automatically controlling luminescent tubes comprising in combination a

transformer connected to one of said tubes, a three electrode electron tube adapted to supply said transformer with oscillating current, a filament heating circuit for said tube, means for periodically opening and closing said filament heating circuit, and means in said filament heating circuit for progressively changing the resistance thereof upon operation of said first mentioned means.

4. An apparatus for automatically controlling luminescent tubes comprising in combination a transformer connected to one of said tubes, a three electrode electron tube adapted to supply said transformer with oscillating current, a filament heating circuit for said electronic tube, means for periodically opening and closing said filament heating circuit, and an incandescent lamp inserted in series in said filament heating circuit for progressively changing the resistance thereof upon operation of said first mentioned means.

5. An apparatus for electrically controlling the degree of illumination of a luminescent tube and the formation of luminous beads or nodules therein, comprising a three electrode electron tube, a filament heating circuit for said electron tube, a plate circuit for said tube, means for periodically opening and closing said filament circuit, an oscillating circuit fed by said plate circuit, means connecting said plate circuit with the luminescent tube and means for progressively tuning the last mentioned circuit.

6. An apparatus for electrically controlling the degree of illumination of a luminescent tube and the formation of luminous beads or nodules therein, which comprises in combination, a source of alternating current, two three electrode electron tubes including each a filament circuit and a plate circuit, means for connecting the last mentioned tubes to said source of current in such a manner as to allow current to flow through one tube for one direction of the current and to flow through the other tube for the other direction of the current, means for periodically opening and closing the filament circuits of these tubes, and means for coupling the plate circuits of the last mentioned tubes with the luminescent tube.

7. An apparatus for electrically controlling the degree of illumination of a luminescent tube and the formation of luminous beads or nodules therein, which comprises in combination, a source of alternating current, two three electrode electron tubes including each a filament circuit and a plate circuit, means for connecting the last mentioned tubes to said source of current in such a manner as to allow current to flow through one tube for one direction of the current and to flow through the other tube for the other direction of the current, means for periodically opening and closing the filament circuits of these tubes, means for coupling the plate circuits of the last mentioned tubes with the luminescent tube, and means for progressively varying the current flowing through either of the three electrode electron tubes.

DANIEL PAUL ALBERT ANDRÉ KAYSER.
